(57) **CLAIM**

We claim the ornamental design for a cutlery handle, as shown and described.

DESCRIPTION

This application is related to U.S. patent application Ser. No. 29/382,055 filed Dec. 28, 2010 and U.S. patent application Ser. No. 29/382,059 filed Dec. 28, 2010.

FIG. 1 is a perspective view of a cutlery handle according to the new design;

FIG. 2 is a left side elevation view of the cutlery handle shown in FIG. 1;

FIG. 3 is a right side elevation view of the cutlery handle shown in FIG. 1;

FIG. 4 is a top view of the cutlery handle shown in FIG. 1;

FIG. 5 is a bottom view of the cutlery handle shown in FIG. 1;

FIG. 6 is a front end view of the cutlery handle shown in FIG. 1; and,

FIG. 7 is a rear end view of the cutlery handle shown in FIG. 1.

Features shown in broken lines form no part of the claimed design.
